WELL FLOWING APPARATUS

William L. Clark, Oklahoma City, Okla.

Application July 31, 1934, Serial No. 737,717

11 Claims. (Cl. 103—232)

My invention relates to apparatus for lifting oil or other liquid from wells.

The prime object of my invention is to provide a liquid lifting apparatus which will function by the introduction of a fluid under pressure within the well at a point below the normal liquid level.

Other objects of the invention are to provide a device of this class which may be selectively attached for operation to a usual well casing at any desired point within the well; which is so designed that the lifting fluid cannot exert back pressure upon the producing stratum; which may be withdrawn from the well through a column of oil therein without bodily lifting the column; which may be lowered into a well upon the bottom of a string of usual production tubing and may utilize the weight of such tubing in packing between the device and the well casing; which embodies a positive means for insuring its release from the well when its withdrawal is desired; and, which is positive in action as well as simple in construction.

The device consists substantially of a plurally perforated central tubular element attached to and communicating with the lower end of a string of production tubing, a body surrounding the tubing and open at each end to permit the passage of liquid, a foot valve for closing the body at its lower end when downward pressure is exerted thereon, means for selectively positioning the body within a well casing, means for accomplishing a fluid tight packing between the exterior of the body and the interior of the well casing, and means for releasing the packing means when desired.

With these and other objects in view as will more fully appear hereinbelow, my invention consists in the construction, novel features, and combination of parts hereinafter more fully described, pointed out in the claims hereto appended, and illustrated in the accompanying two sheets of drawings, of which,

Figure 1 is an elevational sectional view of the upper portion of the device;

Fig. 2 is a similar view, only partially in section, of the lower portion of the device;

Fig. 3 is a fragmentary elevational view partially in section and detailing the means for insuring release of the packing element; and,

Fig. 4 is an exterior elevational view of the device.

Like characters of reference designate like parts in all the figures.

It is understood that various changes in the form, proportion, size, shape, weight and other

details of construction, within the scope of my invention may be resorted to without departing from the spirit or broad principle of my invention and without sacrificing any of the advantages thereof; and it is also understood that the drawings are to be interpreted as being illustrative and not restrictive.

The inventive idea involved is capable of receiving a variety of mechanical expressions one of which, for the purpose of illustrating the invention, is shown in the accompanying drawings wherein:—

The reference numeral 1 indicates the lower end of the lowermost section of a string of usual production tubing disposed within a usual well casing 2. A swage nipple 3 and a collar 4 act as means for connecting the tubing 1 to a central tubular element 5 having a plurality of through perforations 6. The lower end of the element 5 is connected by a collar 7 to the upper end of a valve guide 8.

Surrounding the lower and smaller portion of the nipple 3 is the upper end of a body head 9 which is provided with a plurality of outlet ports 10. The head 9 is keyed to the nipple 3 by a key or keys 11 in such a manner that it is permitted longitudinal movement with relation to the nipple but is prevented from independent rotation with relation thereto. The collar 4 acts to limit the longitudinal movement of the head 9 in a downwardly direction while the larger upper portion of the nipple 3 limits such movement in a reverse direction.

An interiorly threaded sleeve 12 having a plurality of small through perforations 13 acts as a means for connecting the lower end of the head 9 to the upper end of a tubular body 14 which concentrically surrounds the element 5 and the lower end of which is threadedly connected by a collar 15 to the upper end of a foot element 16 provided at its lower end with a plurality of inlet openings 17. Vanes 18 are preferably provided between the element 5 and the body 14 in order that proper relation between the two is at all times maintained.

The foot element 16 is provided with a valve seat 19, and a valve body 20 having a depending stem 21 and an upstanding stem 22 is slidably mounted within the element 16 and is adapted to seat upon the valve seat 19 when at the lower end of its throw. The stem 21 passes through the lower end of the foot element 16 and its protruding portion is equipped with a nut or nuts 23 to limit the upward movement of the valve body 20. The stem 22 passes

upwardly into the valve guide 8 and is equipped with a head 31, the office of which is more fully described hereinbelow. An annular disc 32 having a through perforation 33 is held in place 5 within the collar 15 by the upper end of the foot element 16. The office of the disc 32 will also be more fully described hereinbelow.

Surrounding the exterior surface of the body 14 is a tapered element 24 within which the 10 body 14 may slide, and surrounding the body 14 and lying between the lower end of the sleeve 12 and the upper end of element 24 is a resilient packing element 25 which may be distorted to engage the inner surface of the casing 2 and form a fluid tight seal between the body and the casing when the sleeve 12 is moved toward the element 24. The dotted lines in Fig. 1 illustrate the packing element in its sealing position.

20 Toothed slips or exteriorly deformed wall gripping elements 26 are slidably mounted upon the exterior of the body 14 directly below the tapered element 24 and springs 27 act to normally hold the slips in contact with the body. The 25 slips are also rotatable upon the body and their lower ends are connected to a sleeve 28 which has a depending hook 29. The hook 29 normally engages a pin 30 carried by the body 14, but rotation of the body within the collar will disengage the hook from the pin and permit the slips to be moved into contact with the tapered element 24 at which time the element 24 will spread the slips into a gripping engagement with the casing 2 and position the device in the well. 30 The springs 27 are so formed that they press outwardly against the casing with sufficient pressure to permit the body to be rotated and to be moved longitudinally within the sleeve 28 and slips 26.

40 Operation

The device will be lowered into the well upon the string 1 of production tubing to a desired point, such point being such that the perforations 6 in the element 5 are submerged in the liquid in the well. During the lowering operation the head 9 is supported by the upper end of the collar 4 which, together with the element 5, and the valve guide 8 are then at the uppermost end of their limited travel with relation to the head 9, body 14, and the foot element 16. The valve body 20 is at this time held open by the head 31 upon the stem 22 contacting the lower end of the valve guide 8. It may be here stated that the opening in the bottom of the guide 8 is somewhat larger in diameter than the diameter of the stem 22, and that the bottom of the guide 8 and the head 31 are so shaped that the opening is at no time closed by the head 31.

60 The springs 27 during this operation frictionally engage the interior surface of the casing 2. When the desired point is reached the tubing will be rotated in a right hand direction by rotative power applied at the surface of the earth, and the hook 29 will be disengaged from the pin 30, the keys 11 acting to impart a similar rotative action to the body 14 when the tubing is rotated. After the hook is disengaged from the 65 pin 30 the device will be lowered a slight distance which, due to the pressure of the springs 27 on the casing, will inject the tapered element 24 between the slips 26 and cause them to be forced outwardly into a gripping engagement with the 70 casing. Further downward movement of the tub-

ing will cause the head 9 to contact the enlarged portion of the swage nipple 3 and consequently the lower end of the collar 12 will compress the packing element 25 against the upper end of the tapered element 24, and will deform it sufficiently to cause it to seal between the outer wall of the body 14 and the inner wall of the casing 25.

80 Since the valve body 20 is in an unseated position during the lowering operation, when the device is lowered into the fluid in the well the fluid will enter the body 14. After the device is set as above described and the packing has been deformed, a column of liquid will stand above the device and the device will also be filled with liquid. The valve body 20 at this point in the operation is free to move according to the direction of liquid or fluid pressure applied thereto. A suitable fluid under pressure, such as gas, air or steam, will next be injected into the tubing 1 and will flow outwardly through the perforations 6 into the body 14. This fluid pressure will force the liquid in the body outwardly into the casing above the packing element 25 through the outlets 10 and the liquid thereabove will be forced by the fluid to the surface of the earth.

85 When the device is withdrawn from the well the upper end of the head 9 is again supported by the collar 4, and the valve body 20 is again held in an unseated position by the head 31. This permits any liquid then standing in the 90 device to escape through the inlet openings 17. When the weight of the tubing string is picked up off the packing and the slips, they both return to their normal positions. The tapered element 24 is, of course, withdrawn from contact with the 100 slips. Obviously, the device will function and will produce through the tubing 1 if the fluid under pressure is introduced into the casing instead of into the tubing.

105 In Fig. 3 is illustrated a means whereby the 110 motive fluid or the liquid as the case may be, may be ejected through the perforations 13 in the sleeve 12 in order that any accumulation of sediment or extraneous matter which might have settled upon the packing element 25 may be removed or washed away, and to insure that the element 25 may be released from contact with the casing and may assume its original shape and position contiguous with the exterior of the body 14.

115 In order to accomplish this purpose, a removable plug 34, preferably made of wood, having a diameter substantially equal to the inside diameter of the element 5 is lowered through the tubing 1 upon a cable or line 35, and its lower 120 end is seated upon the previously described disc 32. The plug 34 is of a sufficient length to extend upwardly into the element 5 to a point above all except the uppermost ones of the perforations 6 and is adapted to close the perforations there- 125 below when in its seated position upon the disc 32.

130 When the plug 34 is in its seated position and fluid pressure is injected into the tubing 1, the upper end of the plug causes the fluid to be ejected from the element 5 into the body 14 through 135 the uppermost ones of the perforations 6 which are preferably made smaller than the ones therebelow and which are positioned in substantial alignment with the inner ends of the perforations 13 of the sleeve 12. The fluid will consequently be ejected from the body 14 through the perforations 13 at a high velocity and will consequently wash away any sediment upon the packing element 25 even though no column of liquid is standing in the casing above the device. Of course a 140

- quantity of the fluid will escape into the casing 2 through the perforations 10 in the head 9, but the fluid may be delivered at the upper end of the tubing 1 at sufficient pressure and volume to insure the release of the packing element. 5
- Obviously, the invention is susceptible of embodiment in forms other than that which is illustrated in the accompanying drawings and described herein, and applicable for uses and purposes other than as detailed, and I therefore consider as my own all such modifications and adaptations and other uses of the form of the device herein described as fairly fall within the scope of my invention. 10
- Having thus described my invention, what is claimed and desired to be secure by Letters Patent, is:
1. In well flowing apparatus, a tubular body having an outlet and an inlet, a packing element for sealing between the body and a well casing, and fluid means for removing settling from around the packing element. 20
  2. In well flowing apparatus, a tubular body having an outlet and an inlet, a packing element for sealing between the body and a well casing, means for selectively positioning the body with relation to the casing, and fluid means for removing settling from around the packing element. 25
  3. In well flowing apparatus, a tubular body having an outlet and an inlet for well fluid, means for introducing a second fluid under pressure into the body for raising the well fluid therein, a packing element for sealing between the body and the well casing, means for selectively and rigidly connecting the body to the inner surface of the casing at any desired point, and fluid means for removing settling from around the packing element. 35
  4. A device as described in claim 3, in which the connecting means includes wall gripping elements pivotally connected to the body, and means for forcing the elements into contact with the casing. 40
5. A device as described in claim 3, in which the connecting means includes toothed elements connected to the body, and means for forcing the elements into contact with the casing. 5
6. In well flowing apparatus, a perforated section of tubing, a tubular body surrounding the section, said body having an upper outlet and a lower inlet, a check valve for closing the inlet, a packing element surrounding the body intermediate its ends for sealing between the body and a well casing, and means carried by the body for rigidly yet removably connecting the body to the casing at any desired point. 80
7. A device as described in claim 6, and means for removing settling from around the packing element. 85
8. A device as described in claim 6, in which the connecting means includes wall gripping elements pivotally connected to the body, and means for forcing the elements into contact with the casing. 90
9. A device as described in claim 6, and means for controlling the operation of the connecting means from a point at the earth's surface. 95
10. In well flowing apparatus, a perforated section of tubing, a tubular body surrounding the section, said body having an upper outlet and a lower inlet, a check valve for closing the inlet, a packing element surrounding the body intermediate its ends for sealing between the body and a well casing, means carried by the body for rigidly yet removably connecting the body to the casing at any desired point, and means for holding the check valve open when the packing element is out of its sealing position, and when the connecting means is out of connection with the casing. 100
11. A device as described in claim 1, in which the last mentioned means includes structure whereby a fluid may be projected upon the casing and the packing element adjacent their point of contact. 115
